UNITED STATES PATENT OFFICE

CROMWELL A. B. HALVORSON, JR., OF LYNN, MASSACHUSETTS, ASSIGNOR TO GENERAL ELECTRIC COMPANY, A CORPORATION OF NEW YORK.

ARC-LAMP.

1,083,210.

Specification of Letters Patent. Patented Dec. 30, 1913.

Application filed August 3, 1909. Serial No. 511,009.

To all whom it may concern:

Be it known that I, CROMWELL A. B. HALVORSON, Jr., a citizen of the United States, residing at Lynn, county of Essex, State of Massachusetts, have invented certain new and useful Improvements in Arc-Lamps, of which the following is a specification.

This invention relates to electric arc lamps, and its object is to provide a lamp 10 of simple and inexpensive construction, but one which is efficient and of long life.

The invention consists in a lamp having a large upper positive electrode, and two smaller lower negative electrodes abutting 15 against each other at an acute angle, and urged upwardly by a single spring, whereby the pressure on both electrodes will be the same and their rate of feed will be uniform. As the point of contact of said negative 20 electrodes remains practically stationary, the arc is struck by simply lifting the positive electrode, and the length of the arc, being determined by the distance between said upper and lower electrodes, will remain 25 constant.

The several features of construction are clearly shown in the accompanying drawings, in which—

Figure 1 is a front elevation of the lamp, 30 partly in section; Fig. 2 is a perspective view of a portion of the spark gap and cut out; Fig. 3 is an edge elevation of the lamp, partly in section; Fig. 4 is a front elevation of the upper electrode and its supporting devices; Fig. 5 is a top plan view of the same; Fig. 6 is a section of the spark gap; Fig. 7 is a top plan view of the lamp, and Figs. 8 and 9 are diagrammatic views showing the operation of the mechanism.

The several parts are mounted on a platform 1 preferably circular and having an integral box-like recess 2 opening downward, and a similar but smaller recess 3 opening upward, both recesses extending 45 above and below the plane of the platform, as best shown in Fig. 3. At the center of the platform is an opening surrounded by the upright chimney 4 to carry off the fumes rising from the arc. The canopy and 50 the globe are supported on the platform, but are not shown in the drawings.

The lower negative electrodes 5 are preferably composed of magnetite or some other compound producing a flaming or luminous

arc. They are slipped into tubular holders 55 arranged at an angle to each other, so that the upper ends of the electrodes abut, as shown in Fig. 1. The holders are rigidly secured to the end of a depending bracket 7 whose upper end is bolted to the wall of the 60 recess 2, but is thoroughly insulated therefrom by the washers 8 of asbestos or other refractory insulating material. Each holder is slotted longitudinally to admit a follower, preferably the lever 9, which bears against 65 the lower end of the electrode. The levers are fulcrumed at 10 between two bars 11 connecting the holders, and are connected by a link 12, pivoted to one lever at 10' above its fulcrum and to the other one at 10" below its fulcrum and serving to equalize their 70 movements and cause them to rise and fall together. A tension spring 13 connects the lower ends of said levers through the intermediary of link 12, and urges their free ends 75 upwardly in the holders. The electrodes 5 are thus maintained in close contact and are fed upward as they burn away so that their meeting point is stationary and always at 80 the same distance from the reflector. Furthermore, as the spring pressure on one electrode is always the same as that on the other, there is no tendency for one to ride past the other, as would be likely to occur if each electrode was driven by a separate spring. 85 I regard this construction as a valuable and important feature of my lamp.

The upper or positive electrode 14 is of larger cross section than the negative and may be composed of carbon, copper or other 90 good conductor. It is attached at its upper end to a transverse wide and thin bar 15 whose ends are received in jaws at the ends of a U-shaped frame 16. Cotter-pins 17 may be thrust through said jaws and bar 95 to fasten them together. The frame 16 is secured to a flange 18 on a plate 19 which has ears 20 hinged upon a pin 21 passed through the walls of the recess 2 and near the bracket 7. Insulation 22 is interposed 100 between the flange and the frame. A connecting-rod 23 is pivoted to the flange by a pin 24 and is also pivotally attached to one end of a yoke-shaped lever 25 fulcrumed on the chimney, which it surrounds. The 105 other end of said lever is pivotally connected to the movable core 26 of a solenoid 27 mounted on the top of the platform in the

recess 3. The core preferably carries a disk armature 28, which assists in holding the lever down when its solenoid is energized. In Figs. 1, 3 and 8 the lamp is not in circuit, and the heavy upper electrode 14 has dropped down upon the lower ones. But when current is passed through the solenoid it pulls down its core and lifts the electrode 14, thus drawing an arc between said electrode and the lower ones, as indicated in Fig. 9.

In order to cut out the lamp when the lower electrodes burn out, I provide a bridging contact 29 carried by and insulated from a rod 30 which is suspended from a lateral extension of the lever 25 and passes down through the platform 1. Secured to the under side of said platform and insulated therefrom by the washer 31 are two metallic contact plates 32 adapted to be connected by the bridging contact 29. Each contact plate has a binding screw 33 extending up through the platform and insulated therefrom. The line terminals are connected with these binding screws by the conductors *a*, *b*, and one of said line terminals is also connected by a conductor *a'* with the binding screw 34 which is attached to the bracket 7 carrying the lower electrodes. The binding screw 33, connected to the other line terminal is also connected by a conductor *c* with the solenoid 27, whose other terminal is connected by the flexible conductor *d* with a finger 35 extending from one end of the bar 15 up through an opening in the platform, said opening being provided with an insulating bushing 37.

The operation of the cut-out device is as follows: During the normal operation of the lamp, when the lower electrodes 5 abut against each other, the arcing face of the two electrodes is stationary and is at such an elevation that the electrode 14, when it comes into engagement with the abutting electrodes does not descend sufficiently to bring the contact 29 into engagement with the contacts 32. When, however, the useful portion of the lower electrodes 5 has been consumed, the levers 9 engage the ends of the slots in which they operate and no longer impel the electrodes upwardly, the electrodes no longer abut against each other, with a consequence that, with a further consumption of the electrodes, their arcing faces are lowered. Now, when the upper electrode 14 comes into engagement with the lower electrodes, the anode is sufficiently lowered to bring the contact 29 into engagement with the stationary contacts 32 and thus cut-out the lamp.

Arms 38, 39 of resilient metal depend from the contact plates 32 and are slightly indented to receive the pointed ends of two copper plugs 40, 41 which are slipped into

a sleeve 42 of insulating material. Internal ribs 43 on the sleeve engage with shoulders on the plugs and prevent them from coming into actual contact, which would short-circuit the lamp. The plugs are separated by an air space forming a spark gap which will permit a disruptive discharge of approximately 300 volts, so that the device serves to protect the lamp from injury due to a lightning discharge or other abnormal rise of voltage.

This lamp has the advantage of having no mechanism for feeding the electrodes save the levers 9 and spring 13. The single solenoid operates merely to draw the arc by lifting the upper electrode, and when the upper positive electrode is made of copper or other non-consuming material, the length of the arc is constant. The chimney is directly above the arc and there is nothing to impede the escape of the fumes from the flaming electrodes.

In accordance with the provisions of the patent statutes, I have described the principle of operation of my invention together with the apparatus which I now consider to represent the best embodiment thereof; but I desire to have it understood that the apparatus shown is only illustrative; and that the invention can be carried out by other means.

What I claim as new and desire to secure by Letters Patent of the United States, is:—

1. An arc lamp having a platform containing a recess opening downwardly, a chimney rising from said recess, a second recess opening upwardly, a flanged plate pivoted in the downwardly opening recess, a U-shaped frame attached to said flange, a bar supported at the ends of said frame, an electrode mounted on said bar, and a solenoid seated in said second recess for lifting said plate, frame and electrode.

2. In an arc lamp, a consuming electrode, means for feeding said electrode so as to maintain its arcing face fixed with reference to the frame of the lamp, means for stopping the feed of said electrode at a predetermined point whereby further consumption of said electrode causes its arcing face to recede, a co-operating non-consuming electrode, means for bringing said second electrode into engagement with said consuming electrode and separating it therefrom to establish the arc, and a cut-out co-operating with said second electrode and adapted to be closed only when the arcing face of said second electrode is advanced beyond the normal position of the arcing face of said consuming electrode.

3. In an arc lamp, a lower consuming electrode, means for feeding the electrode so as to normally maintain its arcing face fixed with reference to the frame of the lamp, means for stopping the feed of said electrode

at a predetermined point whereby further consumption of said electrode lowers its arc-ing face, an upper non-consuming electrode, means for bringing said upper electrode into engagement with the lower electrode and separating it therefrom to establish the arc, and a cut-out coöperating therewith adapted to be closed only when the arc-ing face of the

upper electrode drops below the normal arc-ing face of the lower electrode.

In witness whereof, I have hereunto set my hand this thirty first day of July 1909.

CROMWELL A. B. HALVORSON, Jr.
